UNITED STATES PATENT OFFICE.

JOHN SIGISMUND RYAN, OF OTAHUHU, NEW ZEALAND.

COOL CHEST OR CHAMBER.

Application filed April 21, 1927, Serial No. 185,486, and in New Zealand February 11, 1927.

This invention relates to a special construction or formation of cool chest or chamber for use in the storage of perishable products or foods or for any other such like purpose.

The said construction embodies special means whereby currents of air may be cooled and passed through the storage chamber, such means depending for their action upon

10 the well known natural principle exemplified by the cooling of a body of water through its exposure to rapid evaporative action, as when contained within a receptacle the walls of which are of porous nature.

15 The invention consists in a construction of device, that may vary in size and shape to suit its special circumstances, and comprising a storage chamber having suitable provision for sealing it and for access thereto

20 combined with a water holding chamber, the walls of which are of a porous nature, and a pipe coil, or coils, arranged within such water chamber and connected at the outlet end or ends with the lower end of the 25 storage chamber, and at the inlet end or ends with any means for sending air through the coil or coils. This air therefore passes through the coil or coils, to be cooled by the surrounding water and is admitted into the

30 bottom of the storage chamber and then passes up through such storage chamber and out through an escape vent or vents arranged in or near the top thereof.

The said device or appliance may be made 35 as a single article in varying sizes suitable for households, boarding establishments and hotels, employing the same general features of construction. It may, however, be made as a compound article in which the two 40 chambers are made separate and of different materials or by a combination of these methods of construction. The air sent in to the storage chamber may also, if required, be subjected to a series of cooling actions by 45 its passage through more than one coil on its way to the storage chamber.

The pressure to send the air supply through the coil or coils and through the storage chamber, may be obtained in any manner that is found suitable in each case, the means or method of so doing forming no 50 feature of this invention.

In fully describing the invention reference will be made to the accompanying sheet of drawings, in which an article, comprising 55 the storage and the water chamber as a single article of manufacture, is shown.

In such drawings:—

Figure 1 is a sectional plan of the article, the section being taken on the line 1—1 of 60 Figure 2.

Figure 2 is a sectional side elevation of the article.

According to the form shown, the article is made of a shape to provide a storage chamber A and a water chamber B separate 65 from each other by a divisional wall C and of a material of a suitably rigid and porous nature, as for instance, an unglazed porcelain or pottery ware. If desired the portion of the walls surrounding the storage chamber A may be treated with any desired waterproofing medium, or such chamber may be lined with any desired material.

The chamber A may be fitted up as a safe 70 with shelves or other supports and is made with an opening for access thereto. In the form shown in the drawings it is made with an open top and such top has an airtight cover D fitted thereon which cover also extends over the water chamber B.

The wall of the chamber A, near its top, is pierced with one, or more apertures E, to act as escape vents for the air currents.

The water chamber B is adapted to be 85 filled with water, as through an opening d formed in the cover D, and may be provided with a draining cock F fitted into its bottom end.

Placed within the said water chamber is 90 a pipe coil G, preferably coiled to extend round near its walls, and up through the height thereof. The inlet H to such coil passes in through the wall of the chamber, near the bottom thereof, while its outlet J 95 extends down inside the chamber and passes through the wall C into the chamber A near its bottom.

If desired, instead of a single coil G, as shown, two or more coils similarly arranged 100 and connected may be employed, or two or more coils connected to form a continuous passage, may be used.

It will be apparent that, the chamber B

being filled with water, such water is cooled, and kept cool, by the evaporation that takes place through its porous walls. When air therefore is forced, or induced, to pass in and through the coil G and from thence into the chamber A, the air will be cooled by the surrounding water and will enter the chamber A and pass upward therein in its cooled state.

10 I claim:—

An air cooled safe, comprising a container divided vertically by an integral wall into two compartments arranged side by side, said dividing wall and the external walls of 15 one compartment being relatively less porous

than the external walls of the other, an air coil arranged in said more porous compartment and adapted to communicate with said less porous compartment near the bottom thereof, said more porous compartment having a quantity of cooling water therein surrounding said air coil, an air-tight cover fitting over both of said compartments, and means for connecting said coil to a supply of air under pressure, whereby air may be 20 forced through said water cooled coil and discharged into said less porous compartment.

In testimony whereof, I affix my signature.
JOHN SIGISMUND RYAN.
